J. H. COYNE

FIRE KINDLER

Filed Nov. 3, 1920

James H. COYNE.

INVENTOR.

BY

Watson E. Coleman

ATTORNEY.

UNITED STATES PATENT OFFICE.

JAMES H. COYNE, OF PORT TOWNSEND, WASHINGTON.

FIRE KINDLER.

Application filed November 3, 1920. Serial No. 421,579.

To all whom it may concern:

Be it known that JAMES H. COYNE, a citizen of the United States, residing at Port Townsend, in the county of Jefferson and State of Washington, has invented certain new and useful Improvements in Fire Kindlers, of which the following is a specification, reference being had to the accompanying drawings.

10 This invention relates to fire kindling means, and has for its object to provide means of this character including all the necessary material for starting a fire.

Another object is to provide kindling means of this character arranged in the form of a bundle, said bundle being capable of being placed upon the grate of the stove without disarranging the various inflammable materials within the bundle and without 20 causing the material to come in contact with the hands of the user.

Another object is to provide kindling means of this character wherein various sizes of kindling wood are used, said wood 25 being of such shape as to permit the circulation of air through the bundle so that the device will instantly ignite when a match is applied thereto.

A still further object of the invention is 30 to provide a kindler of this character including layers of inflammable material, each layer increasing in density from the bottom to the top of the bundle so that the lower layers will quickly burn, said rapidity decreasing as the more solid material is reached at the top of the bundle.

A still further object of the invention is 40 to provide a kindler of this character comprising a plurality of layers of inflammable material, said layers being held in position and prevented from leaving the bundle by means of a paper sheet which serves as a binder therefor, said paper sheet also preventing the hands of the user from becoming soiled when depositing the kindler within the stove.

With the above and other objects in view, the invention consists in the improved construction and arrangement of parts to be 50 hereinafter more particularly described, fully claimed and illustrated in the accompanying drawings, in which:—

Figure 1 is a perspective view of a fire kindler constructed in accordance with an 55 embodiment of the invention,

Figure 2 is a fragmentary side elevation and sectional view, and

Figure 3 is a side elevation.

Referring to the drawings, 5 designates a sheet of paper, which serves as a binder or wrapper for the kindling material. Disposed upon the intermediate portion of one side of the sheet 5 and extending longitudinally thereof is a layer 6 of kindling wood, said wood being formed into relatively 60 coarse or thick strips and disposed in parallel relation to each other. In the formation of the fire kindler, the layer 6 is disposed at the bottom of the bundle but when the kindler is disposed in the stove, the 70 layer 6 is positioned uppermost or forms the upper layer. Disposed upon the layer 6 and coinciding therewith is a layer 7 of kindling wood, said wood being of a medium size, or a size smaller in diameter or width than the 75 wood composing the layer 6. In this way the space left between the sticks composing the layer 6 are filled by means of the narrow strips composing the layer 7, but at the same time a sufficient space is left to permit air 80 to circulate between the layers and the material forming the layers.

Disposed upon the layer 7, is a layer 8 of bituminous matter such as asphaltum or vegetable substance such as resin, the layer 85 8 coinciding with the layer 7. This layer, of course responds very quickly to any fire applied to the kindler and thereby causes the layers 7 and 6 to readily ignite. The layer 8 also serves as a binder to hold the 90 remaining layers in bundle form. Disposed upon the layer 8, is a layer 9 of excelsior and relatively fine or thin pieces of kindling wood, the two elements being combined in one layer.

After the layers have been positioned as above described, the side portions 10 of the sheet 5 are extended toward each other into engagement with the sides of the layers, longitudinally thereof. In this way, a substantial channel is formed by the sheet 5 which holds the various layers in position, and prevent escape of portions of said layers when the same is subject to vibration, heat or like forces. A string 11 or like inflammable fastening means is passed around the center or end portions of the bundle, to firmly secure the paper sheet in engagement with the side portions of the layers 6, 7, 8 and 9 and the bottom portion of the layer 6.

- When it is desired to use the kindler, it is so positioned that the layer 6 is disposed up-
permost so that the layer 9 will engage the
grate of the stove. It will be noted that
5 when applying the kindler to the grate the
sheet 5 protects the hand of the user from
coming in contact with the bituminous layer
so that soiling of the hand is impossible.
Furthermore the layers are substantially
10 disposed in a hood so that fuel applied to
the surface of the sheet 5 will not interfere
with the kindling operation of the various
layers of the kindler, when the match is ap-
plied, the layer 9 being formed of material
15 which ignites very rapidly, the layer will be
quickly consumed and the fire gradually in-
creased in size, and its rapidity decreased
by the density of the layers it encounters
so that when the fire reaches the layer 6, the
20 same will be readily ignited and will burn a
sufficient length of time to permit the fuel
deposited on the kindler to ignite fully. The
paper sheet 5, of course will be consumed
before the flame reaches the layer 6 so that
25 the draught through the fuel is not inter-
fered with.
- These kindlers may be made in any length
desired, but preferably in lengths capable
of being readily applied to conventional
30 sizes of stoves and grates, a number of
kindlers being disposed in a carton so that
the user can procure a quantity at one time,
at the same time eliminating the necessity of
providing a carton for each kindler.
- 35 From the foregoing it will be readily seen
that this invention provides a novel form
- of fire kindler which contains all of the ma-
terial necessary to rapidly and efficiently
kindle a fire, the material while being in-
flammable, is of such a nature that it will not 40
explode or cause damage, and as the layers
increase in density as the flame spreads, the
danger of fuel falling through the grate be-
fore the same is ignited is eliminated, as the
layer 6 of coarse kindling wood will support 45
the fuel until the same is ignited. It is not
necessary to use additional wood, as the ma-
terial is so arranged that the flame is not
only large but is maintained a sufficient
length of time to permit the fuel to prop- 50
erly ignite.
- What is claimed is:—
- A fire kindler comprising a bundle in-
cluding a sheet of paper, a layer of coarse
sized kindling wood disposed longitudinally 55
of the intermediate portion of said sheet, a
layer of medium sized kindling wood dis-
posed upon the coarse sized kindling wood,
a layer of asphaltum disposed upon the me-
dium sized kindling wood, and a combined 60
layer of fine sized kindling wood and ex-
celsior disposed upon said asphaltum layer,
and means for holding the side portions of
said paper sheet in engagement with each
side portion of said layers, whereby the 65
bundle may be inverted to dispose the last
mentioned layer on the bottom of the bundle
without disarranging the remaining layers.

In testimony whereof I hereunto affix my
signature.

JAMES H. COYNE
